UNITED STATES PATENT OFFICE.

OLIN II. BASQUIN, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,969, dated December 7, 1897.

Application filed October 23, 1897. Serial No. 656,223. Term of patent 14 years.

To all whom it may concern:

Be it known that I, OLIN II. BASQUIN, a citizen of the United States, residing at Chicago, in the county of Cook and State of Illinois, have invented a certain new and original Design for Prism-Lights, of which the following is a description.

My invention relates to designs for prism-lights.

Figure 1 is a plan view of a prism-light embodying my design; Fig. 2, a section therethrough.

A is the body of the prism-light; B B, a series of prisms on one side thereof placed at a certain angle; C C, a series of other prisms at a different angle on the same side of the light and arranged so as to form a design. When seen from the prism side, a prism-surface is presented composed of a field of prisms of a

certain angle and a figure or design formed 20 of other prisms of a different angle, and when viewed from the other side of the plate the sets of prisms are distinguishable from each other, so as to produce a field and a design 25 therein.

The essential features of my design are found in a prism-light comprising a substantially flat body with prisms on one side, some of the prisms at a given angle to form a field, and the remaining prisms set at a different 30 angle to form a design.

I claim—

The design for a prism-light, substantially as shown and described.

OLIN II. BASQUIN.
